UNITED STATES PATENT OFFICE.

ALBERT HAASE, OF ESSEN-ON-THE-RUHR, GERMANY, ASSIGNOR TO FRIED. KRUPP AKTIEN-
GESELLSCHAFT, OF ESSEN-ON-THE-RUHR, GERMANY.

PROJECTILE.

932,014.

Specification of Letters Patent. Patented Aug. 24, 1909.

Application filed December 14, 1907. Serial No. 406,525.

To all whom it may concern:

Be it known that I, ALBERT HAASE, a subject of the Emperor of Germany, and a resident of Essen-on-the-Ruhr, Germany, have 5 invented certain new and useful Improvements in Projectiles, of which the following is a specification.

The present invention relates to projectiles of the type which is composed of a 10 steel core, a mantle closed at the bottom and leaving the point of the core exposed, and a filling of soft metal interposed between the core and the mantle. In accordance with the present invention such projectiles are improved in such a manner that 15 they can be easily and inexpensively manufactured, by reason of their simple construction, and have a hitherto unobtainable penetrating force relatively to targets offering great resistance (armor-shields, armor-plates and the like).

By way of example the accompanying drawing shows the invention applied to a projectile for an army rifle, the figure showing 20 the projectile partly in axial longitudinal section and partly in elevation and on an enlarged scale.

The core of the projectile is made from hard steel and consists of the point A and 25 the shank A'. The point A may be of any suitable formation. In the drawing it is shown as having the shape of a pointed arc. The shank A' is cylindrical throughout the greater part of its length and is of smaller 30 diameter than the greatest diameter of the point A while being of greater diameter than half the caliber of the projectile. Near the point the shank is provided with an undercut portion a². The cylindrical part 35 of the shaft is longer than the combined lengths of the underent portion and the point. The shank A' of the core is surrounded by the mantle B which is provided with a bottom b' and is made from nickel, 40 copper or the like. The mantle is cylindrical on the part nearest the bottom b', the cylinder being of an outer diameter corresponding to the caliber, and the remaining part of the mantle gradually tapers toward 45 its annular edge b². The point A of the core rests on the edge b² and the outer surface of the mantle is flush with the surface of the point A. The space between the mantle B and the shaft A' of the core is filled with a co-

herent mass C of soft metal of high specific 55 gravity, such as lead. The undercut portion a² of the core and the gradual taper of the mantle prevent the core from moving in a direction away from the bottom b' of the mantle.

If an army-rifle projectile of this construction hits an armor-shield, such as commonly used for field-guns, the filling C is violently upset, bursts the mantle B and detaches itself from the core A together with the mantle. The core A then continues its travel alone. When the projectile penetrates the armor the kinetic energy of the entire projectile thus acts on the core which has a smaller diameter than the projectile. This 70 property the improved projectile has in common with the known armor piercing projectiles of this type but has further the advantage of having a hitherto unobtainable penetrating force for the following reasons: 75 In the first place the mantle B and the filling C lie against a projection on the core of the projectile and consequently transmit all their kinetic energy to the core on impact. Secondly, the resistance offered to the bursting by the coherent mass of the filling C and by the mantle B is very great and the time during which the mantle and the filling act on the core entering the armor-shield is 80 therefore as long as possible. There is a further advantage in the peculiar shape of the core which on the one hand has the result that the core, after its point has penetrated the armor-shield, does not come in 85 further frictional engagement with the walls of the hole made by the projectile; on the other hand, the shape of the core results in favorable conditions as regards the resistance of the air in the part of the path of flight lying behind the shield.

The projectile retains its original shape when penetrating the bodies of human beings or animals as in this instance the resistance met with is not sufficient for effecting the sudden retarding of the velocity of 100 the projectile which is required for the upsetting of the filling and the bursting of the mantle.

Having thus described the invention, what is claimed and desired to be secured by Letters Patent is:

1. A projectile consisting of a cylindrical mantle open at one end, said open end being

- provided with a taper; a hard metal core having a solid conoidal point whose base rests upon the annular edge of said mantle and whose convex surface extends flush with the outer surface of said mantle, and a shank embodying a cylindrical portion within the cylindrical portion of the mantle and an undercut portion within the tapered portion of said mantle; and a soft metal filling occupying the entire annular space between the mantle and the core and serving to lock the core to the mantle by means of said undercut portion of shank.
2. A projectile comprising a mantle with a tapered open end; a conoidal point abutting against the annular edge of said tapered open end and having a depending shank integral therewith, said shank having a straight cylindrical portion greater in diameter than one half the caliber of the projectile and an undercut portion between the point and cylindrical portion; and a filling within the annular space between the mantle and the shank.
3. A projectile comprising a mantle, a conoidal point connected with said mantle, a shank integral with said conoidal point, said shank being provided with an undercut portion of less diameter than the rest of the shank; and a soft metal filling within the annular space between the shank and the mantle and projecting into said undercut portion of the shank to lock the shank and point to the mantle.
4. A projectile consisting of a core of hard metal having a point and a shank having an undercut portion adjacent to the point, a mantle closed at the bottom and surrounding said shank and having its outer surface extending flush with the surface of said point, and a filling interposed between the shank and the mantle; said shank being cylindrical throughout a portion of its length greater than the combined lengths of the point and said undercut portion.
5. A projectile consisting of a core of hard metal having a point and a shank, a mantle closed at the bottom and surrounding said shank and having its outer surface extending flush with the surface of said point, and a filling interposed between the shank and the mantle; said shank being cylindrical throughout the greater part of its length and having an undercut portion adjacent to said point; the diameter of the cylindrical part of the shank being smaller than the greatest diameter of the point and more than half the caliber of the projectile.
6. A projectile comprising a core of hard metal having a shank and a point, a mantle closed at the bottom and surrounding said shank, and a filling of soft metal interposed between the shank and the mantle; said shank being throughout of smaller caliber than the base of the point and having its greatest caliber for the greater part of its length essentially constant.
7. A projectile comprising a core of hard metal having a shank and a point, a mantle closed at the bottom and surrounding said shank, and a filling interposed between the shank and the mantle and consisting of a single coherent piece of soft metal, said mantle having its outer surface extending flush with the surface of the point, and said shank being throughout of smaller caliber than the base of the point and having its greatest caliber for the greater part of its length essentially constant.
8. A projectile comprising a core of hard metal having a shank and a point, a mantle closed at the bottom and surrounding said shank, and a filling interposed between the shank and the mantle and consisting of a single coherent piece of soft metal, said mantle abutting with its open end against the base of said point and having its outer surface extending flush with the surface of the point; and said shank being throughout of smaller caliber than the base of the point and having its greatest caliber for the greater part of its length essentially constant.
9. A projectile comprising a core of hard metal having a shank and a point, said shank having an undercut portion near the point, a mantle closed at the bottom and surrounding said shank; and a filling of soft metal interposed between the shank and the mantle and projecting into said undercut portion of the shank to lock the mantle to the shank; said shank being throughout of smaller caliber than the base of the point and having its greatest caliber for the greater part of its length essentially constant.
- The foregoing specification signed at Dusseldorf, Germany, this 24th day of October, 1907.
- ALBERT HAASE.
- In presence of—
- WILHELM FLASCHIE,
CLEMENS HECKMANN.
